UNITED STATES PATENT OFFICE

JAMES EASTWICK, OF FYNING WOOD, ROGATE, ENGLAND.

AUTOMATIC SMALL-ARM.

1,109,910.

Specification of Letters Patent.

Patented Sept. 8, 1914.

Application filed June 13, 1914. Serial No. 845,015.

To all whom it may concern:

Be it known that I, JAMES EASTWICK, a subject of the King of Great Britain, residing at Fyning Wood, in the parish of Rogate, in the county of Sussex, England, have invented a new and useful Automatic Small-Arm, of which the following is a specification.

This invention relates to automatic small arms of the type in which the opening of the breech is effected by the forward lurch, on the discharge of the piece, of a weight which is capable of moving a short distance relatively to the rest of the breech mechanism.

A weapon constructed in accordance with my invention is shown by way of example in the accompanying drawings but I wish it to be understood that I do not restrict myself to the exact form illustrated as many of the details of my invention may be considerably varied.

Figure 1 is a longitudinal section showing portions of a weapon in the uncocked position; Figs. 2 and 3 are cross-sections on the lines A—A, B—B, of Fig. 1; Fig. 4 is a plan partly in section of the casing; Figs. 5 and 6 are sections on the lines C—C, D—D, of Fig. 4; Fig. 7 is a left side view of the rear part of the casing; Fig. 8 is a perspective view of the hand cocking lever; Fig. 9 is a left side view of the front of the casing; Fig. 10 is a longitudinal section of the bolt; Fig. 11 is a cross section showing the bolt and ejector; Fig. 12 is a plan of the raceway on which the breech mechanism moves; Fig. 13 shows the two parts of which the weight is composed. Fig. 14 is a right hand elevation of a modified form of casing; Fig. 15 a half horizontal section; Fig. 16 a plan; Fig. 17 an end view thereof; and Figs. 18 to 22 are sections or half sections on the lines numbered accordingly in Fig. 14.

The barrel 1 is screwed into a receiver 2 forming part of or rigidly attached to the raceway 3 and at its fore end, which is not shown, it is secured to the stock in any convenient way permitting the barrel to move through a small distance relatively to the stock. The raceway is attached by flanges 4 to a casing 5 secured to the stock by binding screws 6 extending through the wood-work, which is not shown, and the base plate 7 of the trigger guard in the usual way. This casing dovetails at each end into

a block 8 into which the binding screws engage. The sides of the casing are bent over and leave a longitudinal slot along the center. The receiver and weight 9 when in their respective forward positions close the front portion of this slot; the remainder is closed by a flap 10 hinged on one of the sides and opening at right angles to the axis. A movable end piece 11, seen best in Fig. 7, fits into the rear of the side pieces so as to complete the casing and is held in position by a stud 12 actuated by a helical spring 13 arranged on the axis of the hinge of the flap and tending to keep the flap closed as well as to keep the end piece in position. This casing not only excludes dirt but also prevents the motion of the weight being seen. In disassembling, the binding screws 6 are removed, the fore end of the barrel freed from the stock and then the barrel, raceway and casing lifted clear of the wood-work. The dovetailing then permits the casing to be taken off piecemeal without using any tool.

14 is a bolt carrier inclosed within the weight and which carries the bolt 15 having on its front end locking lugs 16 adapted to enter grooves 17 in the receiver so that the bolt can be locked thereby in the receiver.

18 is a firing pin passing axially through the bolt and having formed on it lands engaging rifled grooves 19 on the interior of the bolt. Surrounding the firing pin is a firing spring 20 and also an unlocking spring 21, these two springs being kept apart, so that they may not rub one upon the other, by a sleeve 22 extending rearward from the bolt carrier. When the piece is fired the weight lurches forward relative to the rest of the mechanism, or more strictly remains stationary owing to its inertia and does not partake in the first portion of the recoil, and thereby compresses the springs 20 and 21. The firing pin is thereupon, as is explained later, locked to the weight so that the spring 20 cannot expand until the trigger is again pulled to fire but the spring 21 immediately expands and therefore the weight is thrown backward again to the relative position shown in Fig. 1 carrying with it the firing pin. This rearward motion of the firing pin turns, through the lands and rifled grooves, the bolt in its bolt carrier and so frees the lugs 16 and the bolt

is therefore free to move rearward out of the receiver, and the weight, bolt carrier,

etc., move rearward along the raceway compressing two telescopic closing springs 23 which are contained in tubes of which the rear halves 24 are connected to the rear of the raceway while the front halves 25 are connected to the weight. While the bolt is thus at the rear, the spent cartridge is ejected and a fresh cartridge is raised from the magazine in any convenient way and then the springs 23 expand bringing the weight and parts within it back to the position shown in Fig. 1 except that the firing pin is still held back, that is, the weapon is cocked. Moreover at the commencement of recoil and during the lurch of the weight, the barrel, raceway and magazine have recoiled relatively to the stock and in so doing have compressed two recoil springs 26 arranged between the rear block 8 and the casing 27 of the magazine. These springs are of such a strength that they expand again during the backward travel of the weight so that the raceway is urged forward relatively to the stock by these springs 26 while the weight is traveling rearward relatively to the stock by the spring 21, coupled with the effect of recoil, the result of these movements being an increase of power in the weight.

30 The casing 27 of the magazine is rigidly attached to the raceway so as to slide with it. The magazine casing is left open below, the bottom of the magazine being formed by the base plate of the trigger guard. At the proper point a portion 28 of this base plate is made to swing on a pivot 29 and is secured by a spring catch 30 or other convenient means. If it be swung down ready access is obtained to the interior of the magazine from below without disassembling the weapon. The trigger gear is attached to the raceway and is connected with the trigger 31 by a bar 32.

45 A retaining clutch 33 is attached to the raceway by a pivot 34 so that when the weight and the raceway are in their forward positions the weight is secured to the raceway but on the recoil before the backward motion of the weight begins the clutch is removed and then cannot return to its place until the weight and raceway are again in their forward positions. This clutch is so arranged as also to secure the raceway to the casing and is operated by the trigger. 50 Moreover it prevents any premature trigger action due to "involuntary pull" or otherwise without any separate timing arrangement.

60 The trigger 31 presses by means of a bell crank 35 against the arm 36 of the retaining clutch 33. In the uncocked position in addition to the bolt being locked home, the weight 9 is held by a tooth 37 of the retaining clutch and the end 38 of the clutch 65 rests against the rear block 8. The weight

is thus secured to the raceway and the raceway to the stock. The action of cocking by hand explained below unlocks the bolt but does not further alter the position. Then on pulling the trigger the arm 36 is pressed back, the tooth 37 is lowered but not sufficiently to release the weight altogether and the end 38 of the clutch is raised so that the sloping surface 39 is placed against a corresponding slope 40 on the rear block 8. At the same time the bar 32 is drawn back, the trigger spring 41 is partly compressed, a bell crank 42 pivoted to the magazine casing is moved and a plunger 43 is thereby lifted until it comes nearly against the front end of the clutch 33. The upper end of the plunger now presses up the forward end of the sear 44 thus throwing the sear out of the bent 45 on the firing pin 18 and the piece fires. It is this sear which catches the bent 45 when the weight lurches forward and locks the firing pin to the weight so keeping the spring 20 compressed as referred to above. On the commencement of recoil the incline 39 is forced against the slope 40 on the rear block 8, the spring 41 is further compressed, a spring flap 47 on the bell crank 42 is freed from the plunger 43, the tooth 37 is lowered out of the way of the rearward travel of the weight and the front end of the clutch 33 presses down the plunger 43 into its original position. A tooth 48 on the sear when the latter is out of bent enters a recess 49 in the raceway so that at the end of the forward lurch the tooth is forced backward and the sear raised into bent.

55 The whole mechanism is now free to move until both the raceway 3 and the weight 9 return to the positions shown. Then the spring 41 rotates the clutch 33 on its pivot into the position shown and at the same time moves back the bell crank 42, the flap 47 opening and so slipping past the shoulder 50 on the plunger and the piece is ready to fire again.

50 is the hand cocking lever; it is pivoted at 52 near the rear end of the weight and works in the vertical plane through the axis of the weapon. When at rest this lever lies on the top of the weight; in this position it slides under the hinged flap 10 with the backward movement of the weight. When rotated on its pivot through a right angle it raises the hinged flap and at the same time it draws back the firing pin by cams 53 formed on it near its pivot pressing on horizontal studs 54 formed on the end of the firing pin 18. At the same time a projection 55 formed on the lever beyond the pivot presses down a tooth 56 on the retaining clutch 33 so as to free the weight and also presses up the sear 44 into bent and then the lever 51 standing upright forms a handle by which the weight is 130

drawn to the rear, the lever still holding up the flap 10 as it passes along the slot in the casing.

As a safety arrangement I employ a pin 57 actuated by a screw 58 in the upper part of the receiver, see Fig. 2; a quarter of a turn of a handle 59 attached to the screw depresses this pin until it forms a continuation of one of the lugs 60 of the receiver 2 so that the lugs 16 of the bolt 15 are unable to turn and consequently the firing pin cannot go forward. This fractional turn also brings the handle 59 into the line of sight so that aim is impossible until the safety gear is replaced. The handle projects through the slot in the casing and works backward and forward in it with the motion of the receiver.

I provide an immobilizing gear for converting the weapon into a single loader. This gear (shown in Figs. 1, 4, 5 and 9) consists of a lever 61 readily turned on its pivot 62 by the thumb of the left hand and kept in position by a spring 63 housed in the forward binding screw 6. This lever raises blocks 64 through the casing on each side of the receiver or the barrel between studs 65 on it and some part of the weight so as to prevent at once the backward movement 30 of the barrel and any forward lurch of the weight.

I provide an extractor of any convenient type and an ejector consisting of a short L or T piece, shown in Figs. 10 and 11, the longer limb 66 thereof runs in a groove in the bolt 15 and works through a slot in the front face of the bolt while the shorter limb 67 works in a groove 68 of the proper shape formed in the raceway and seen in Fig. 12. As the weight recoils the limb 67 comes against a bar 69 lying in the groove 68 with its rear end resting against a cross bar 70 at the rear of the raceway which also acts as the abutment for the closing springs. In disassembling the cross bar is removed by slipping or rotating it out of position and then the hand lever 51 being worked the weight and bolt are slipped off the raceway to the rear, the closing springs and the bar 50 69 coming away at the same time. The bar then impinges against the cross bar at the proper point in the travel and it has a head which prevents it being drawn out of the tube unless the bolt is freed from the carrier. The weight is formed in two parts (shown 55 separately in Fig. 13) kept together by the screws forming the pivot 52 of the lever so that when withdrawn by the soldier the weight and bolt with its gear remain united but when the screws are removed by the 60 armorer the lever and the two parts of the weight come apart and the bolt, the carrier and the locking and unlocking springs are removed.

In the modification shown in Figs. 14 to

22 the casing consists of two parts 71 hinged to plates 72 secured to the stock. When closed in position they are held by catches 73, 74. Each catch is controlled by the spring 13 of the flap 10. When the flap is 70 raised it presses this spring forward by means of inclines 75 and this tends to secure the catches and hold the casings in position. The catch 73 is connected by a crosshead 76 with a spindle 77 passing through the axis 75 of the spring. This spindle at its farther end engages with a crosshead 78 formed on the catch 74.

A spring 79 tends to force the casings apart so that if not securely held they fall 80 apart as shown by the dotted lines in Figs. 18 to 22. When thus open the casings can be closed by simply snapping them together. When closed they can be opened by pressing the crosshead 78 rearward.

The parts may be disassembled as follows:—The spindle 77 is pressed back by the pressure of thumb or finger on a stud 80 on the spindle until the crosshead 78 is clear; 85 78 is then swung outward and the catch 74 90 is drawn out. The stud 80 is then pressed back to the full extent so as to get the crosshead 76 clear of the casing, the stud is then unscrewed and taken off and the spindle 77 and the spring 13 taken out toward the 95 front. The closing springs 23 are here shown as running on a central spindle 81.

What I claim is:—

1. In an automatic small arm, the combination of a stock, a barrel, a raceway fast therewith, a recoil spring between the stock and the raceway, a breech bolt, a weight, a spring between the bolt and the weight, and means actuated by this spring for unlocking the bolt. 100

2. In an automatic small arm, the combination of a stock, a barrel, a magazine and a raceway fast therewith, a recoil spring between the stock and the raceway, a breech bolt, a weight, a spring between the bolt and the weight, and means actuated by this spring for unlocking the bolt. 110

3. In an automatic small arm, the combination of a stock, a barrel, a raceway fast therewith, a recoil spring between the stock 115 and the raceway, a clutch adapted normally to lock the raceway to the stock, a trigger, means actuated by the trigger for releasing the raceway from the stock, a breech bolt, a weight, a spring between the bolt and the weight, and means actuated by this spring for unlocking the bolt. 120

4. In an automatic small arm, the combination of a stock, a barrel, a raceway fast therewith, a recoil spring between the stock 125 and the raceway, a breech bolt, a weight, a spring between the bolt and the weight, means actuated by this spring for unlocking the bolt, a clutch adapted normally to lock the raceway and weight to the stock, a trig- 130

ger, means actuated by the trigger for releasing the raceway from the stock, and means actuated by the recoil for withdrawing the clutch from the weight.

5. 5. In an automatic small arm, the combination of a stock, a barrel, a raceway fast therewith, a recoil spring between the stock and the raceway; a breech bolt, a weight, a spring between the bolt and the weight, 10 means actuated by this spring for unlocking the bolt, a clutch adapted normally to lock the raceway and weight to the stock, a trigger, means actuated by the trigger for releasing the raceway from the stock, a hand 15 lever pivoted on the weight and adapted to unlock the bolt and to release the weight from the clutch.

6. In an automatic small arm, the combination of a stock, a barrel, a raceway fast 20 therewith, a recoil spring between the stock and the raceway, a breech bolt, a weight, a spring between the bolt and the weight,

and a casing surrounding the weight and breech mechanism and secured to the stock.

7. In an automatic small arm, the combination of a stock, a barrel, a raceway fast 25 therewith, a recoil spring between the stock and the raceway, a breech bolt, a weight, a spring between the bolt and the weight, and a casing surrounding the weight and 30 breech mechanism and formed in two parts each of which is longitudinally hinged to the raceway.

8. In an automatic small arm, the combination of a stock, a barrel, a raceway fast 35 therewith, a recoil spring between the stock and the raceway, a breech bolt, a weight, a spring between the bolt and the weight, and means for locking the barrel to the stock and for preventing the lurch of the weight. 40

JAMES EASTWICK.
